CLAIM

The ornamental design for a flash drive, as shown and described.

DESCRIPTION

FIG. 1 is a front, top, and left side perspective view of a first embodiment of the flash drive;

FIG. 2 is a front, top, and right side perspective view thereof;

FIG. 3 is a left side view thereof;

FIG. 4 is a right side view thereof;

FIG. 5 is a front plan view thereof;

FIG. 6 is a back plan view thereof;

FIG. 7 is a top plan view thereof;

FIG. 8 is a bottom plan view thereof;

FIG. 9 is a front, top, and left side perspective view of a second embodiment of the flash drive;

FIG. 10 is a front, top, and right side perspective view thereof;

FIG. 11 is a left side view thereof;

FIG. 12 is a right side view thereof;

FIG. 13 is a front plan view thereof;

FIG. 14 is a back plan view thereof;

FIG. 15 is a top plan view thereof; and,

FIG. 16 is a bottom plan view thereof.

The broken lines in the drawings illustrate environmental subject matter and form no part of the claimed design.
